UNITED STATES PATENT OFFICE.

HOWARD KEYNTON, OF WEST HOBOKEN, NEW JERSEY.

VALVE FOR RADIATORS OR THE LIKE.

1,213,108.

Specification of Letters Patent.

Patented Jan. 16, 1917.

Application filed February 9, 1912. Serial No. 676,509.

To all whom it may concern:

Be it known that I, HOWARD KEYNTON, a citizen of the United States, residing at West Hoboken, in the county of Hudson and

5 State of New Jersey, have invented certain new and useful Improvements in Valves for Radiators or the like, of which the following is a specification.

This invention relates to valves for use in 10 connection with steam radiators or the like, and aims to provide certain improvements therein.

The object of the present invention is to 15 provide a valve of simple and inexpensive construction which is adapted to be connected with a steam radiator, and to permit the slow passage of steam outwardly from the radiator, but to prevent the return passage of air into the radiator when the steam is 20 closed off from the latter.

The principal object of valves of this type is to prevent the filling of the radiator with air, which is required to be displaced when the steam is turned on. Moreover, if any air 25 is present in the radiator the valve permits its escape as soon as steam is introduced into the radiator.

In the accompanying drawings illustrating the invention, Figure 1 is a side elevation, with parts in section of one form of the invention; Fig. 2 is a vertical section thereof on line 2--2, Fig. 3; Fig. 3 is a top plan 30 of the device, with the cap removed.

Referring to the drawings, the valve comprises a casing A, the lower part of which is formed with screw-threads B, this portion being of suitable diameter to screw directly into a radiator X or a fitting connected with the radiator. The portion B is preferably 40 tapered so that a leak-tight fit may be obtained without the necessity of a packing. The casing A is also provided with wrench faces such as C, by means of which the valve may be applied to the radiator. Above the 45 wrench faces C is a portion D which is preferably of less diameter than the screw-threaded portion B, and wrench face C.

The casing is provided with an internal bore E extending preferably the full length 50 thereof, but also preferably of different diameters. In the construction shown the lower part of the bore is of the maximum diameter and is formed with a screwthread F. Above the screwthread F is a restricted 55 portion or shoulder G which serves as a seat

for the valve seat H. Above the seat G the bore E is somewhat constricted, and at the top of the shell or casing it may be still further constricted as shown at I.

The valve which I prefer to use in connection with the casing is of the Schrader type, and comprises a valve proper J formed as a cup carrying a packing K of suitable material adapted to withstand a high heat and considerable pressure. The valve seat H is 60 of tubular construction, and is provided with a packing ring L which is designed to be pressed against the shoulder G by a screw-threaded plug M which is adapted to engage the screwthread F of the casing. The plug 65 M and valve seat H are preferably connected together so that they can not become disconnected, and preferably also are relatively rotatable so that as the plug M is screwed inwardly the valve seat is not turned, but is 70 pressed longitudinally inward. By this means the distortion of the packing L is prevented. To the valve proper J is fastened a pin N which passes through the valve proper, the valve seat, and the plug, 75 the end of the stem being flattened as shown to prevent these parts from becoming disconnected, and to limit the upward movement of the valve. The plug is provided with 80 screw-driver projections Y by which it may 85 be rotated.

At the top of the casing I preferably provide a cap O for the purpose of keeping dust or other foreign matter from entering the shell, and in order that the cap shall not 90 prevent the escape of steam, I provide a passage through which the latter may escape, thus assuring that the radiator will always be full of steam whenever there is any pressure of steam in the radiator. In 95 the construction shown this is accomplished by making a flat portion or portions P upon the upper end of the casing, and preferably also notching the casing at Q, so that when the cap is screwed home, steam or air may 100 escape downwardly around its edge.

By this invention several advantages are obtained. The valve shell is of simple and inexpensive construction. The valve parts are freely removable from the interior of the 105 shell, so that in case of necessity they can be easily removed, replaced or repaired. At the same time as they are inserted from the bottom of the shell, they cannot be tampered with by children or others. This fea- 110

ture is of importance, since if the valve parts were removed when steam was turned on, there would be liability of burning those near the radiator. The type of valve parts shown is particularly adapted for the purpose in question, since it is light in weight and positive in action. The restricted opening I at the top of the casing is sufficient to permit the slow leakage of steam, while insufficient to permit the introduction of any article which would be liable to injure the valve. The cap O provides a means for excluding dust or the like, which in the construction shown is liable to enter the shell and injure the valve. At the same time a free passage for the steam or air is permitted.

Although I have described with great particularity an embodiment of my invention, I do not deem my invention necessarily limited to such precise form, as modifications may be made therein within the limits of the appended claims.

What I claim is:—

1. A valve for radiators or the like comprising a casing having means thereon adapted to engage a part to which the valve is to be attached, and a central bore, a shoulder in said bore, a valve proper provided with a resilient packing, and a separable valve seat having a packing adapted to engage said shoulder, said valve proper and valve-seat being adapted to be inserted in said bore from the inner end thereof, and said valve proper being adapted to open outwardly to provide a vent from the interior of the radiator to the atmosphere, and to close inwardly to prevent entrance of air from the atmosphere when the pressure in the radiator falls below atmospheric pressure.

2. A valve for radiators or the like, comprising a casing having means thereon adapted to engage a part to which the valve is to be attached, and a central bore, said casing having screw-threads at the inner end of said bore and a shoulder within said bore, a valve proper provided with a resilient packing, a separable valve-seat, said valve proper and valve seat being adapted to be inserted in said bore from the inner end thereof, and a screw-threaded member adapted to engage the screw threads in said bore to hold said valve-seat against said shoulder, said valve proper being adapted to open outwardly to provide a vent from the interior of the radiator to the atmosphere, and to close inwardly to prevent entrance of air from the atmosphere when the pressure

in the radiator falls below atmospheric pressure.

3. A valve for radiators or the like, comprising a casing having means thereon adapted to engage a part to which the valve is to be attached, and a central bore, a valve proper in said bore, a valve stem, a vent in said bore, said valve proper being adapted to open outwardly to allow exit of fluid to the atmosphere, and to close inwardly to prevent entrance of air from the atmosphere when the pressure in the radiator falls below atmospheric pressure, and means on said valve stem for preventing said valve proper from closing said vent when pressed away from its seat.

4. A valve for radiators or the like, comprising a casing provided with exterior screw-threads adapted to engage a part to which the valve is to be attached, and a central bore, said casing having screw-threads at the inner end of said bore and a shoulder within said bore, a valve proper provided with a resilient packing, a separable valve-seat, said valve proper and valve seat being adapted to be inserted in said bore from the inner end thereof, and a screw-threaded member adapted to engage the screw threads in said bore to hold said valve-seat against said shoulder, said valve proper being adapted to open outwardly to provide a vent from the interior of the radiator to the atmosphere, and to close inwardly to prevent entrance of air from the atmosphere when the pressure in the radiator falls below atmospheric pressure.

5. A valve for radiators or the like, comprising a casing having means thereon adapted to engage a part to which the valve is to be attached, and a central bore, a valve proper provided with a resilient packing, and a separable valve seat having a packing adapted to engage said casing, said valve proper and valve seat being adapted to be inserted in said bore from the inner end thereof, said valve proper being adapted to open outwardly to provide a vent from the interior of the radiator to the atmosphere, and close inwardly to prevent entrance of air from the atmosphere when the pressure in the radiator falls below atmospheric pressure.

In witness whereof, I have hereunto signed my name in the presence of two subscribing witnesses.

HOWARD KEYNTON.
